Patented Nov. 28, 1916.

UNITED STATES PATENT OFFICE.

PETER DESMORE, OF SEATTLE, WASHINGTON.

ARTIFICIAL HAND.

1,206,753.

Specification of Letters Patent. Patented Nov. 28, 1916.

Application filed November 2, 1915. Serial No. 59,172.

To all whom it may concern:

Be it known that I, PETER DESMORE, a citizen of the United States, residing at Seattle, in the county of King and State of Washington, have invented certain new and useful Improvements in Artificial Hands, of which the following is a specification:

This invention relates to artificial hands; and its object is the provision of a strong and durable hand of this character, easily actuated and controlled, and whereby a great variety of operations may be performed.

The invention consists in the novel construction, adaptation and combination of parts, as will be hereinafter described and claimed.

In the accompanying drawings, Figure 1 is a pictorial representation of my improved hand illustrated as fitted to a person. Fig. 2 is a side elevation of the hand proper and its wrist connection with a stump socket. Fig. 3 is a plan view thereof shown partly in horizontal section. Fig. 4 is a front elevation of the same. Figs. 5 and 6 are detail transverse sectional views through 5—5 and 6—6, respectively, of Fig. 2.

The appliances illustrated are for use with an arm which has been amputated below the elbow but it is apparent that they may be used where the amputation is made thereabove by employing any suitable artificial arm.

The reference numeral 1 designates a stump socket which is connected to a person's arm by lacings 2 and suspensory straps, such as 3, at the front and back, from an upper-arm band 4 which is suspended from his shoulder by a strap 5. The strap 5 bears upon and is connected to a shoulder support 7 held in place by a band 8 encircling the chest of the wearer immediately below the arms. Rotatably connected to the outer end of the stump socket 1 is a plate 9 which is provided with a circular rack 9¹ having its teeth engageable by a spring-pressed dog 10 to secure the plate in selected rotary positions. Said dog is desirably in the form of a bell-crank having its free end 10¹ protrude from the socket to enable the wearer to press the same against an object for disengaging the dog from said rack and thereby allowing the plate to be rotated.

Rigidly secured to said plate is the flange 55 base 11¹ of a post 11 arranged axially of the socket and carrying at its outer end a cylindrical block or knob 12 of rubber or an equivalent.

13 is a bolt extending diametrically 60 through the post 11 for securing a finger 14 in offset relation thereto and to prevent said finger from turning about the axis of said bolt the latter is formed with a polygonal portion 13¹ (Fig. 6) which fits into correspondingly shaped holes 11² and 14¹ of the respective parts.

The finger 14, hereinafter designated as the "rigid" finger, has hingedly connected thereto at the rear of the bolt 13, a movable 70 finger 15 by means of a pivotal pin 16 which is disposed above a plane extending through the axis of the post.

The forward ends of both the fingers extend forwardly and thence laterally substantially as represented by 14² and 15² in the views, to a point in front of the knob 12 and a short distance above the axis of the same, as best shown in Fig. 4. The opposing surfaces of the two fingers are desirably formed 80 in planes so that when they are brought together they will be juxtaposed throughout their lengths except that in proximity to its extremity one of said fingers is provided with a recess 17 for the purpose hereinafter 85 explained.

18 is a spring of the so-called "split ring" type having its ends engage in notches 18¹ of the respective fingers to yieldingly hold the movable finger 15 against the rigid one. 90 A pair of bell-crank levers 19 are pivotally connected by studs 20 to the rigid finger between the hinge-pin 16 and the bolt 13. In advance of the latter said levers serve to carry a pin or roller 21 which is accommodated by a groove 22, Fig. 2, of the fixed finger when the two fingers are together. Arms 19¹ of said levers extend above the movable finger and as illustrated are coupled by a pin 23.

24 represents a cable or "cord" as such devices are usually termed, and makes in this instance connections between the shoulder support 7 and the lever-pin 23. More particularly, said cord includes a snap hook 25 105 provided on one end to engage the pin 23 directly or through the medium of a link 26.

and at its other end by a swivel connection 27 is engaged with an eye-attachment 28 secured to the shoulder support. Also included in said cord are turn-buckle devices 5 29 for regulating the effective length of the cord.

30 represents a link attached to the stump socket 1 near its upper end and through which the cord passes, as shown in Fig. 1. 10 The main function of the link 30 is to prevent the cord pressing against a coat sleeve when the arm is flexed, although the link may be made to contribute to the action of the hand.

15 31 is a loop extending upwardly from the movable finger 15 for the purpose of receiving the end of a small article in coöperation with the two fingers between which the article is grasped. In Fig. 3, for example, I indicate by broken lines P a pencil extending through the loop 31 and held by the fingers in the recess 17, which has been found convenient for similar and other purposes.

20 25 In operation, when the wearer straightens his arm a tension is applied through the cord 24 and the bell-crank lever 19 to turn the latter about its fulcrum 20 resulting in the raising of the roller 22 against the underside of the movable finger 15, and the opening movement of the same with respect to the rigid finger 14. Such opening movement of the movable finger is attained in 30 opposition to the spring 18.

35 35 As the roller 22 is elevated and being constrained by the levers, the roller will be carried rearwardly or toward the fulcrum 16 of the movable finger whereby it is evident that the effective power of the levers is greatest at the beginning of the opening movement and gradually diminishes as the roller approaches the fulcrum 16 of the movable finger. By reason of such devices, the wearer can open the fingers with less fatigue 40 and hold them in their open positions with relatively little effort by the wearer. The levers 19 also serve as guides to prevent any lateral movement of the finger 15 to relieve the pin 16 of undue strains.

45 50 The purpose of the knob 12 is mainly to coöperate with the fingers to enable a person to accomplish various actions which are otherwise not readily performed as, for example, in turning a door-knob, the knob 12 of the hand is pressed against the door-knob while the shank of the same is grasped between the finger ends 14¹ and 15¹; the knob 12 being thus held in frictional engagement 55 with the door-knob enables it to be turned 60 by a rotary movement of the person's arm.

The knob 12 may also be used to advantage in turning the pages of a book or newspaper by traversing the upper corner of a page toward the inner edge thereof with 65 the peripheral surface of the knob, as is

oftentimes done with a finger tip of a natural hand.

The invention is of simple and inexpensive construction and is exceedingly useful to a person needing an artificial hand. 70

What I claim, is—

1. An artificial hand comprising a socket adapted to be secured to an arm stump, a post connected with and extending forwardly from said socket, a finger rigidly connected to said post at one side of the latter, a movable finger complementary to the rigid finger and hingedly connected thereto, a cord fastened at one end to the shoulder of the wearer, a bell-crank lever fulcrumed to the rigid finger and connected to said cord to be operated thereby to raise said movable finger by a sliding engagement with the latter. 75

2. An artificial hand comprising a socket 80 adapted to be secured to an arm stump, a plate rotatably connected to the outer end of said socket, means to lock said plate in selected rotary positions, a post rigidly connected to said plate, a finger rigidly connected to said post at one side of the latter, a movable finger complementary to the rigid finger and hingedly connected thereto, a spring tending to yieldingly hold said movable finger in closed relations with the rigid finger, a cord fastened at one end to the shoulder of the wearer, and a bell-crank lever fulcrumed to the rigid finger and connected to said cord to be operated thereby 85 to raise said movable finger by a sliding engagement with the latter. 90

3. An artificial hand comprising a socket 95 adapted to be secured to an arm stump, a knob carried by said socket in axial alinement therewith, a finger carried by said socket in offset relations with the axis of the socket, a second finger hingedly connected to the first named finger, means for yieldingly holding the fingers in closed position, and devices operable from the wearer's 100 shoulder for actuating the fingers in opposition to said means. 105

4. An artificial hand comprising a socket 110 adapted to be secured to an arm stump, a pair of hingedly connected fingers connected to said socket for revolvable movements about the axis thereof, a recess provided in the outer extremity of one of said fingers, a looped projection provided on one of said fingers to coöperate with the aforesaid recess in holding an article grasped between the fingers, a spring tending to retain said fingers in closed relations, a lever fulcrumed to one of said fingers, and means operable 115 from the wearer's shoulder for actuating said lever to engage and eventually move the other finger into open position. 120

5. An artificial hand comprising a socket 125 adapted to be secured to an arm stump, a post extending forwardly from said socket, 130

a finger disposed to one side of said post and rigidly connected thereto, a second finger hingedly connected at its rear end to the rear end of the rigid finger, a lever engageable with the second named finger and fulcrumed to the rigid finger in advance of said hinge connection, and a cord operable from the wearer's shoulder for actuating

said lever to effect the relative opening movements of the fingers. 10

Signed at Seattle, Washington, this 7th day of October, 1915.

PETER DESMORE.
